Assistant Examiner — Kelly L Gross

(57) **CLAIM**

The ornamental design for an infant positioning device as shown and described.

DESCRIPTION

FIG. 1 is a front isometric view of an infant positioning device embodying my new design;

FIG. 2 is a front view of the infant positioning device;

FIG. 3 is back isometric view of the infant positioning device;

FIG. 4 is a right side view of the infant positioning device;

FIG. 5 is a left side view of the infant positioning device;

FIG. 6 is a top view of the infant positioning device;

FIG. 7 is a bottom view of the infant positioning device;

FIG. 8 is a view of the infant positioning device in a state of use;

FIG. 9 is a front isometric view of an alternate embodiment of the infant positioning device; and,

FIG. 10 is a front isometric view of yet another alternate embodiment of the infant positioning device.

The broken lines in FIGS. 1 through 7, 9, and 10, show portions of the infant positioning device that form no part of the claimed design. The broken line infant in FIG. 8 is for

(Continued)

showing the infant positioning device in a state of use and forms no part of the claimed design.

1 Claim, 8 Drawing Sheets
